(57) **CLAIM**

The ornamental design for an interchangeable reflector light fixture, as shown and described.

DESCRIPTION

FIG. 1 is a perspective view of a first embodiment of an interchangeable reflector light fixture, as viewed from above, showing my new design;

FIG. 2 is a reflector component of the interchangeable reflector light fixture shown in FIG. 1, as viewed from above;

FIG. 3 is a reflector component of the interchangeable reflector light fixture shown in FIG. 1, as viewed from below;

FIG. 4 is a left side view of the light fixture shown in FIG. 1;

FIG. 5 is a right side view of the light fixture shown in FIG. 1;

FIG. 6 is a front elevation view of the light fixture shown in FIG. 1;

FIG. 7 is a rear elevation view of the light fixture shown in FIG. 1;

FIG. 8 is a bottom plan view of the light fixture shown in FIG. 1;

FIG. 9 is a top plan view of the light fixture shown in FIG. 1;

FIG. 10 is a perspective view of a second embodiment of an interchangeable reflector light fixture, as viewed from above, showing my new design;

FIG. 11 is a reflector component of the interchangeable reflector light fixture shown in FIG. 10, as viewed from above;

FIG. 12 is a reflector component of the interchangeable reflector light fixture shown in FIG. 10, as viewed from below;

FIG. 13 is a left side view of the light fixture shown in FIG. 10;

FIG. 14 is a right side view of the light fixture shown in FIG. 10;

FIG. 15 is a front elevation view of the light fixture shown in FIG. 10;

FIG. 16 is a rear elevation view of the light fixture shown in FIG. 10;

FIG. 17 is a bottom plan view of the light fixture shown in FIG. 10;

(Continued)

FIG. 18 is a top plan view of the light fixture shown in FIG. 10;
 FIG. 19 is a perspective view of a reflector engaging component of an interchangeable reflector light fixture, as viewed from above, showing my new design;
 FIG. 20 is a perspective view of the reflector engaging component of an interchangeable reflector light fixture, as viewed from below, shown in FIG. 19;
 FIG. 21 is a left side view of the reflector engaging component of an interchangeable reflector light fixture, shown in FIG. 19;
 FIG. 22 is a right side view of the reflector engaging component of an interchangeable reflector light fixture, shown in FIG. 19;
 FIG. 23 is a front elevation view of the reflector engaging component of an interchangeable reflector light fixture, shown in FIG. 19;
 FIG. 24 is a rear elevation view of the reflector engaging component of an interchangeable reflector light fixture, shown in FIG. 19;
 FIG. 25 is a top plan view of the reflector engaging component of an interchangeable reflector light fixture, shown in FIG. 19; and,
 FIG. 26 is a bottom plan view of the reflector engaging component of an interchangeable reflector light fixture, shown in FIG. 19.

The broken-line disclosure shown in the views is understood to represent portions of the article in which the claimed design is embodied, but which form no part of the claimed design.
